ABSTRACT: An upswingable, self-threading yarn guide is disclosed, having two legs extending from a single shank to form a bifurcate yarn-gathering structure, one leg intermediate its juncture with the shank being bent downwardly and outwardly as a yarn-gathering guide, and the other leg intermediate its juncture with the shank being bent downwardly and inwardly thereof and terminating in a helical turn away from said first leg so as to receive yarn gathered by said first leg in a yarn-retaining and self-threading function. Also disclosed is a conventional circular holder attached to the shank opposite the legs for attachment to an upswingable yarn guide-holding fixture attached to a textile spinning or twisting machine.

THREAD GUIDE

BACKGROUND OF THE INVENTION

This invention relates to a thread or yarn guide useful in textile machines requiring that the guide be swung upward during the doffing of packages, such as bobbins therefrom, and yet retain the yarn within the guide during such upswing. It also relates to a thread or yarn guide which is self-threading during the winding or unwinding of thread or yarn onto or from a package, and during yarn-piecing or joining operations of an automatic yarn piecing apparatus.

SUMMARY OF THE INVENTION

The present yarn or thread guide comprises a generally U- or V-shaped bifurcate yarn gathering portion having divergently extending legs, one of said legs intermediate the apex joining it with the other leg being bent downwardly and the other leg being bent downwardly and inwardly towards the apex and terminating in a helical turn away from the first leg; a mount or holder portion for releasably securing the yarn guide to the textile machine through some attachment such as a conventional yarn guide fixture adapted to hold the yarn guide, which fixture may be pivotable so as to swing the yarn guide secured thereto upward and out of the way of package being doffed from the machine; and a shank portion joining the bifurcate portion to the mount portion.

THE DRAWINGS

A better understanding of the present invention may be had through the descriptions which follow when taken in conjunction with the appended drawings in which:

- FIG. 1 shows, in plan view, an embodiment of the present yarn guide which is usable with Z-twist yarn; and
- FIG. 2 shows the embodiment of FIG. 1 in elevation.

PREFERRED EMBODIMENT

Turning to the figures, the yarn guide has at one end a U- or V-shaped bifurcate yarn gathering portion, generally 40 designated 10, having an apex or juncture element 18 joining the two divergent legs 12,20 thereof, leg 12 having a downwardly depending element 14 from a bend 16 intermediate leg 12, and leg 20 having a downwardly depending element 22 which is directed inwardly towards apex 18 45 through a bend 24 intermediate leg 20, element 22 terminating with a helical turn 26 pitched in a direction away from or opposite to the divergence of leg 12. At its other end, the yarn guide has a mount portion 28 shown in the form of a semicircular element; joining bifurcate portion 10 to mount portion 28 is a shank portion 30.

OTHER EMBODIMENTS

Many structural modifications may be made from the elements shown in the drawings of the preferred embodiment and yet fall within the scope of this invention to attain the objects of providing a self-threadable and yarn retaining guide. For example, for use with S-twist yarn, the positioning of legs 12,20 would be reversed from that shown with leg 12 to the right of leg 20; further, helical turn 26 may continue as several

turns; shank 30 instead of being a single rodlike element may be plural, or be a plate which may be pivotable through a hinge element intermediate its ends for up- or down-swinging bifurcate portion 10 in the absence of a pivotable yarn guide fixture attached to the machine; further, mount portion 28 may be of any conventional structure well known to the art for releasable securing of the guide to the textile machine.

OPERATION OF THE INVENTION

Generally, the present yarn guide would be fixed to a textile machine through releasable connection between mount portion 28 and some fixture which, in many instances, would be pivoted so as to permit the guide to be swung out of the way of a package of yarn being doffed from the machine. When the guide is so swung, yarn held within helix turn 26 is retained thereby and not lost due to retention by element 22 of leg 20. In certain textile machines, such as spinning or twisting frames, guides are used intermediate the yarn delivery or drafting rolls and the spindle takeup devices for package formation as on a bobbin tube. As the spindles turn, the yarns therebetween are twisted with, conventionally, a "Z" or "S" twist for imparting strength; in such operations it is often desirable to thread the guide while the machine is running; with the present guide, automatic or self-threading is obtained, the turning yarn engaging the inside of leg element 14, being guided around the inside surfaces of leg 12, juncture 18, and leg 20 around bend 24, element 22 and into the annulus of helical turn 26 to be retained therein. If a break in the yarn should occur, it may be pieced manually and the guide threaded as was described; if an automatic piecing device is used, hand threading of a guide is disadvantageous to complete, automatic operations, but through the use of the present guide, after piecing is effected by the device, the yarn will self-thread itself into the guide as was previously described.

Thus, having described the construction, operation and advantages of the invention, that which is claimed is:

1. A thread guide comprising a bifurcate thread-gathering and retaining means having two laterally divergent legs joined to an apex member, one of said legs, intermediate its ends, being bent downwardly and away from said apex member and the other of said legs, intermediate its ends, being bent downwardly and toward said apex member and having its free end terminating in a helical turn which is pitched in a direction opposite to that of the divergence of said one leg.
2. A thread guide as in claim 1 wherein said helical turn has its axis of symmetry normal to the plane of said apex member.
3. A thread guide as in claim 1 wherein said bend of said one leg is closer to said apex member than the bend of said other leg.
4. A thread guide as in claim 1 wherein said apex member is joined to a mounting means for mounting said guide on a textile machine by a shank therebetween.
5. A thread guide as in claim 1 wherein said apex member and said legs form a generally U-shaped structure.
6. A thread guide as in claim 1 wherein said apex member and said legs form a generally V-shaped structure.
